UNITED STATES PATENT OFFICE.

WOODBURN LANGMUIR, OF NEW YORK, N. Y.

DESIGN FOR A CARRIAGE TIRE AND RIM.

SPECIFICATION forming part of Design No. 34,974, dated August 20, 1901.

Application filed June 19, 1899. Serial No. 721,142. Term of patent 7 years.

To all whom it may concern:

Be it known that I, WOODBURN LANGMUIR, a subject of the Queen of Great Britain, and a resident of New York, in the county of New York and State of New York, have invented a certain new and useful Design for a Carriage Tire and Rim, of which the following is a specification.

The drawings show in Figure 1 a cross-section of a tire and rim and in Fig. 2 a perspective view of the same.

As shown in the drawings, the leading or material features of my design consist of the wearing portion C, the top of which is semi-circular in shape, the sides of said wearing portion forming a right angle with the base E, on which it rests, the sides of the flange

A flaring outward, so as to leave a V or wedge shaped space B between the flange A and the perpendicular sides, the sides of the tire in no wise conforming to those of the flange.

Having described my invention, what I claim as new, and desire to secure by Letters Patent, is—

The design for a carriage tire and rim, substantially as herein shown and described.

Signed at New York, in the county of New York and State of New York.

WOODBURN LANGMUIR.
